UNITED STATES PATENT OFFICE

OLIVER H. TAYLOR, OF BROOKLYN, ASSIGNOR TO BENJAMIN C. ANDERSON,
OF NEW YORK, N. Y.

LOCK-HINGE.

SPECIFICATION forming part of Letters Patent No. 350,851, dated October 12, 1886.

Application filed March 25, 1886. Serial No. 196,481. (No model.)

To all whom it may concern:

Be it known that I, OLIVER H. TAYLOR, of Brooklyn, Kings county, in the State of New York, have invented a certain new and useful Improvement in Lock-Hinges, of which the following is a specification.

My improved hinge is intended more especially for window-blinds, and will be described as so applied. It holds the blind in the open position. It engages automatically and is arranged to be braced and sustained efficiently against the great force liable to be impressed on it in severe gales. The two principal parts of the hinge may be of an ordinary construction.

The invention requires only a peculiarly-formed dog and a pivot for connecting it, so that it may rise and sink to be engaged and disengaged. Its form guards against its sinking or rising beyond the required limits.

The accompanying drawings form a part of this specification, and represent what I consider the best means of carrying out the invention.

Figure 1 is a plan view of the hinge. The adjacent portion of the building is shown in section. Fig. 2 is an elevation of the hinge as seen from the left in Fig. 1. Fig. 3 is a front view corresponding to Fig. 2. Figs. 4 and 5 show a modification. Fig. 4 is a plan view, and Fig. 5 is a front elevation.

Similar letters of reference indicate corresponding parts in all the figures where they occur.

A is a portion of the building, B a plate fastened thereon, B' an arm extending out therefrom, and B² a pintle mounted in B'. To the blind C is fixed a stout angular iron, D, having an arm, D', carrying a socket, D², which engages on the pintle B². So far as yet described the hinge is an ordinary and long-approved construction, with the parts so arranged that when the blind is open the arms B' D' shall lie in or near the same plane extending outward from a building.

M is a peculiarly-formed dog, of steel or other suitable material, made by drop-forging or otherwise in the form represented. Certain portions will be designated, when necessary,

by additional marks, as M' M², &c. It is connected to the arm B' by a stout pivot, P, and is formed and bent as shown. The outer end having an arm, M', describes an arc of which the pintle B² is the center, and the lower side of which is beveled, as shown, and provided with a notch, m, adapted to strongly engage with and hold the part D' when the blind is fully open. The body M of the dog lies close alongside of the parts B' D', and when any force—as a strong wind—tends to shut the blind the dog M is braced and supported against the hinge, as will be obvious. Its corner M² striking the plate B supports the dog against sinking too low, and the corner M³ striking the same plate at a higher point guards it against being thrown up too high by any force, as by a sudden impulse in throwing the blind violently open. The bevel on the under side of M' adapts it to engage automatically when the blind is thrown open.

To unlock and allow the blind to be closed, it is necessary simply to apply the finger to the arm M' and lift the dog.

One important advantage of my invention is the security it gives against the blind being lifted. When the dog M is engaged, it not only holds it reliably open, but also guards against its being lifted by wind or other force. So long as the blind is down in its place a finger applied to the dog M will lift it enough to allow the blind to be closed. Whenever it is required to unhang the blind, for repairing or other purpose, the blind may be lifted out of engagement with the hinge by simply lifting the dog and partially closing the blind; but so long as the dog is engaged the blind cannot be lifted off. Any lifting force applied to the blind will raise it a little way, carrying the dog with it; but so soon as the corner M³ strikes the plate B the dog cannot lift higher and the blind cannot raise higher. It is effectually guarded against being unhung while the dog is engaged.

Modifications may be made in the forms and proportions without departing from the principle or sacrificing the advantages of the invention.

Figs. 4 and 5 show a form adapted to serve

on frame buildings, where the arm B' is short, and the pintle B² consequently near the plate B. In this construction the part corresponding to the dog M is pivoted to a point on the plate B, and the curved arm corresponding to M' extends in the general direction to and from the building, instead of, as in the other form, in a general direction parallel to the face of the building. This form of the device works the same, except that the stops for restraining the motion are different. The arm B' serves as the stop to prevent the dog from sinking too low, and the same part serves, being struck by another portion of the dog, as a check to prevent the dog being thrown up too high. This form of the device automatically engages and is disengaged by the same action as the other.

I claim as my invention—

The combination, with the blind-hinge B' 20 B² D', of the dog M, pivoted to the part B', and having an arm, M', formed in an arc having the pintle B² for a center, and provided with an engaging-notch, m, and means for holding said dog against an upward movement 25 sufficient to disengage the two parts of the hinge when the dog is in operation, as set forth.

In testimony whereof I have hereunto set my hand, at New York city, this 18th day of March, 1886, in the presence of two subscribing witnesses.

OLIVER H. TAYLOR.
